FRANK PIRRO DE NOBILI, DECEASED, LATE OF LOS ANGELES, CALIFORNIA, BY
FANNIE PIRRO DE NOBILI, EXECUTRIX, OF LOS ANGELES, CALIFORNIA.

MAIL BOX.

1,404,099.

Specification of Letters Patent. Patented Jan. 17, 1922.

Application filed March 24, 1921. Serial No. 455,282.

To all whom it may concern:

Be it known that FRANK PIRRO De NOBILI, deceased, late a subject of the King of Italy, and a resident in the city and county of Los Angeles, State of California, did invent a new and useful Improvement in Mail Boxes, of which the following is a specification.

The invention relates to improvements in mail boxes, and the object of the invention is to provide a device of this nature which is simple and inexpensive in construction, and in which provision is made to effectually prevent the unauthorized removal therefrom, or the destruction of or tampering with, letters, parcels, or the like, through the inlet opening, once the same has been deposited therein, and thus obviate the risk of theft or destruction of the mail, a possible occurrence in mail boxes not so provided.

The object is attained by the construction illustrated in the accompanying drawing in which—

25 Figure 1 is a face view of the entire mail box;

Figure 2 is a side view of the entire box;

Figure 3 is a cross section taken on the line A—B of Figure 1 as the mail box appears when the flap of the box is closed.

Figure 4 is a cross section taken on the line A—B of Figure 1 as the mail box appears when both ends of the mail box are closed.

35 Figure 5 is a cross section taken on the line A—B of Figure 1 as the mail box appears when the flap and door of the mail box are wide open.

Figure 6 is a plan view of the mail box.

40 Similar figures of reference indicate similar parts throughout the several views.

The mail box consists of a suitably formed casing 1 of any desired shape, being shown substantially rectangular in the drawing, and it is closed on all sides and top and bottom, with a suitable door 2 for the authorized removal of the contents, the front wall of the casing being provided with an opening 3; covering said opening is a flap 4, which is opened and closed by a drip 5, and pivoted to the mail box on pin 8, by pulling upward on the drip 5, the wall 4^b of the flap is moved backward into position so that the opening 3 is unobstructed as shown in 55 Figure 5. In this position the mail box is

ready to receive mail, said mail being put through the opening 3 into the bottom of flap marked 4^c. When the drip 5 is released the inlet opening is closed automatically and covered by flap 4, this motion allowing the 60 mail to drop into the mail box.

At lower portion of the front face of mail box is formed a door 2 which opens and closes on its hinges 12 as shown in Figure 1, and can be securely locked by placing pad 65 lock through 13. Formed at lower portion of door 2 is a glass opening 14 as shown in Figs. 1, 3, 4, and 5, the object of said opening being to see any object that is in the bottom of the mail box; above this opening is 70 formed another opening 15 the object of which is to place an identification card.

The operation of the device and its utility will be apparent, on reference being had to the drawings, particularly Figs. 3, 4 and 5. 75 In Fig. 3 the mail box is shown closed and it will be noted that the opening 3 is completely covered by the flap 4 and that no admittance can be had to the interior of the casing unless the flap 4 is pulled upwardly 80 by means of the drip 5. This has the effect of bringing the parts into the position shown in Figs. 4 and 5, in which it will be seen that the upward movement of the drip 5 will swing wall 4^b backward and flap bottom 4^c forward causing it to completely close the opening to the mail box but at the same time giving access to the mail chute 4^c allowing mail to drop into the mail box, as shown in Figure 3. 90

From the foregoing it will be apparent that the mail cannot be withdrawn through the opening 3.

Positioned on the outside at the bottom of the mail box is a flag or signal 16, which 95 is pivoted to the side of the mail box by means of pin or rivet 17. In the inside of the mail box is a dog 18, which is also pivoted by pin or rivet 17, said dog 18 engages a dog which is attached to the door 2. This 100 dog having a projection 19 which is made of spring material that will only bend forward. The flag or signal 16 is put down in a horizontal position while the door 2 is closed, said flag or signal 16 cannot be released until the door 2 is opened as the projection 19 clasps the dog 18 and when the door 2 is opened the signal or flag 16 being released is then automatically pushed 105 upward to a perpendicular position. 110

It will be seen, therefore, that there has been devised a simple and inexpensive mail box out of which the unauthorized removal of mail, or its destruction, is prevented in a practical and efficient manner.

Limitation is not confined to the complete mail box construction shown, in so far as individual boxes are concerned, as the essential elements of the invention, that is flaps 4, 4^a, 4^b, and 4^c, together with flag attachment, may be applied with equal facility to suitable openings in doors, lockers or any other receptacle provided for the deposit therein of mail or other matter.

15. What is claimed is:

1. A mail box of the character described having a mail inlet 3, flaps 4, 4^b, 4^c and drip 5, flaps 4, 4^b and 4^c being of one piece of metal of curved shape terminating with a 20 parallel straight flap, and connected hingeably and swingably to upper part of the mail box and operated by means of the drip 5; flap 4^b when raised by upward movement of drip 5 opening the inlet opening 3 of the 25 mail box swinging flap 4^c forward causing it to completely close entrance to the inside of the mail box, but at the same time giving

access for the deposit of mail through opening 3, into the bottom of flap 4^c, said flap 4^b when closed through downward movement 30 of drip 5 closing inlet opening 3 which movement of said flap 4^b swings flap 4^c backward thereby opening flap 4^c, so as to permit the mail to drop into the mail box.

2. A mail box of the character described 35 having a mail inlet 3, flaps 4, 4^b, 4^c, and drip 5, and a flag or signal attachment at the lower side section of the mail box pivotally connected with a dog, said flag or signal and dog engaging a dog pivoted at the door 40 of the mail box, said dog pivoted at the door having a projection thereto, the flag or signal being put down in a horizontal position when the door of the mail box is closed, the projection of the dog clasping the dog pivoted to the flag or signal when flag or signal is in the horizontal position, said flag or signal not being releasable until the door of the mail box is opened, which movement automatically pushes the flag or signal upward 45 to a perpendicular position.
